BURIAL APPARATUS

Lloyd V. Troup, Saginaw, Mich.

Application May 25, 1935, Serial No. 23,415

3 Claims. (Cl. 27—26)

This invention relates to burial apparatus, and more specifically to means for supporting the vault base and casket over the grave opening when the services are being conducted at the grave.

5 One of the prime objects of the invention is to design simple, practical, and economical means for supporting the vault base in position over the grave, said means being adjustable to permit them to be swung out of position, so that the grave opening will be free and unobstructed, and so that the vault can be readily lowered.

Another object is to provide a sectional frame around the grave, so that the vault handling apparatus can be readily wheeled into and out of 15 position, and so that it will remain level and true during the vault raising and lowering process.

A further object is to provide a frame and base supporting means which supports the vault base approximately level with the surface of the 20 ground, so that the ferns and other decorating means can be extended over the frame sufficiently to conceal the grave opening from view when the vault base is in position.

A still further object is to design a sectional 25 frame and drop brackets which can be readily assembled and disassembled, and which can be folded into a neat, compact bundle, so that it can be readily transported from one location to another.

30 The above and other objects will appear as the specification progresses, reference being had to the accompanying drawings in which I have shown one embodiment of my invention, and in which like reference numerals indicate like parts throughout the several views thereof.

In the drawings—

Figure 1 is a plan view of a grave opening, showing the sectional frame and the vault base supported in position thereon.

40 Fig. 2 is a sectional edge view.

Fig. 3 is a transverse sectional view showing the drop brackets with the vault base in position thereon.

Fig. 4 is a fragmentary plan view illustrating 45 the manner of connecting the side and end members.

Fig. 5 is an enlarged fragmentary view illustrating the adjustment of the drop hangers, the broken lines showing it swung upwardly and 50 against the end frame member.

Fig. 6 is a fragmentary detail view of one of the drop brackets.

Fig. 7 is a fragmentary side view illustrating the opening for the drop bracket lugs.

55 Referring now more specifically to the drawings

in which I have shown one embodiment of my invention, the grave opening is indicated at "A" and a frame, preferably formed of wood, is placed on the edges of the grave opening and on which the vault handling apparatus (not shown) rolls, said frame comprising spaced apart side members 8 and 9 respectively, and end members 10 and 11 are detachably secured thereto in a manner to be presently described, a strip of bar iron 12 being secured to the inner edge of each side member 10 and serves to confine and guide the vault handling mechanism which travels thereon.

The inner edges of the end members 10 and 11 are also provided with bars 13 which project beyond the ends thereof and engage in slotted openings 14 provided in the side members, short strips 15 being provided on the outer edges of these end members and are adapted to engage the ends of the side members when the frame is assembled, so that it is locked in assembled relation, the usual 20 decoration (not shown) covering the frame and edge of the grave opening which is not covered by the vault base.

Drop hangers 16 and 17 respectively span the grave and support the vault base "B" as shown, 25 each hanger being formed with outwardly projecting lugs 18, terminating in enlarged shoulders 19. These lugs are inserted in openings 20 provided in the bar iron strips 12, said openings being formed as clearly shown in Fig. 7 of the drawings to facilitate the assembly of the lugs 18 and lock the hangers in position, said hangers being spaced a predetermined distance from the end members of the frame and are formed with centrally disposed openings 21, and which accommodate the spring actuated locking pins 22 which are mounted in the end frames, and when these drop hangers are swung upwardly to position as shown in dotted lines in Fig. 5 of the drawings, the pin 22 is released and engages the opening 21 in the 40 drop hanger to hold it in adjusted position, so that the grave opening is free and unobstructed and the burial vault can be freely lowered into the grave.

In practice the vault base "B" is placed on the 45 drop hangers 16 and 17, and when the funeral procession reaches the cemetery, the casket (not shown) is placed thereon; at the conclusion of the services the vault handling apparatus, with the vault cover supported thereby, is wheeled into position, the side members 8 and 9 serving as tracks, this vault handling apparatus being the subject matter of a separate application filed by me under date of February 15th, 1935, Serial No. 6,659. The cover is then lowered on the base and 55

is securely fastened thereto; the entire vault is then raised sufficiently to permit the drop hangers 16 and 17 to be swung upwardly and in alignment with the end members 10 and 11, as 5 above explained, the locking pins 22 securing them in adjusted position, leaving the entire grave opening free and unobstructed so that the vault is readily lowered into position in the grave. The handling mechanism, together with the 10 frame, is then detached and disassembled, and the operation is complete.

This frame and mechanism folds compactly and is readily transportable from one location to another.

15 From the foregoing description it will be obvious that I have perfected a very simple, practical, lightweight, sectional frame and vault supporting brackets, which can be readily assembled and disassembled, and which folds compactly to 20 permit easy and rapid delivery from one location to another.

What I claim is:

1. In a burial apparatus of the class described and comprising a sectional collapsible frame 25 adapted to support a vault base over a grave opening, drop hanger brackets pivotally and detachably connected to the side members of the

frame and adapted to receive said vault base, and means on the frame for engaging and locking the hanger brackets as they are swung upwardly into alignment with the frame.

2. In a burial apparatus of the class described 5 and comprising a sectional collapsible frame adapted to be placed on the edges of a grave opening, means for securing said frame in assembled relation, drop hanger brackets detachably and pivotally connected to the side frame 10 members for supporting a vault base over the grave opening, spring actuated pins mounted in the end members of the frame, and openings in said brackets for engagement by said pins when the brackets are swung upwardly into alignment 15 with the end frame members.

3. In a burial apparatus of the class described and comprising a sectional collapsible frame adapted to form a track for a wheeled vault handling apparatus and to support a vault base 20 over a grave opening, said frame including interlocking end and side members formed with metal edges on the inner rim thereof, and drop hanger brackets detachably connected to the metal edges 25 of the side frame members for supporting said vault base in position above the grave opening.

LLOYD V. TROUF.
